BOOT STRETCHER

Elia Galterio, Denver, Colo.

Application October 2, 1948, Serial No. 52,492

4 Claims. (Cl. 12—129.3)

1

This invention relates to a boot stretching device and has for its principal object the provision of a boot stretcher which can be easily inserted in a boot and by means of which a boot may be stretched at any desired point without affecting the size thereof at other points.

A further object of the invention is to provide a simple, easily used and efficiently operating stretcher by means of which a boot may be selectively stretched for length and width of the foot portion and for width at either the top or bottom of the leg portion as desired.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a back view of the improved boot stretcher;

Fig. 2 is a side view thereof;

Fig. 3 is a top view thereof;

Fig. 4 is a vertical sectional view taken on the line 4—4, Fig. 1;

Fig. 5 is a similar sectional view taken on the line 5—5, Fig. 4; and

Fig. 6 is a detail sectional view taken on the line 6—6, Fig. 4.

The improved stretcher comprises an expandable leg portion adapted to be inserted in the leg of a boot and an expandible foot portion hingedly mounted on the leg portion and adapted to be inserted in the foot of a boot. The leg portion may be selectively expanded either at its top, its bottom or both and the foot portion may be selectively expanded both as to width and length. The various expanding actions are all accomplished from the top of the stretcher after it is in place in the boot.

The leg portion of the device consists of a front leg portion 10 and a rear leg portion 11 joined by means of toggle links. The toggle links are arranged in two groups consisting of eight links each. The upper group comprises two sets of four links 12 and the lower group is similar and also comprises two sets of four links 13.

The two sets of links 13 are arranged at opposite sides of a vertical operating shaft 14 and the four links of each set are hinged together at their extremities to form collapsible quad-

2

rangles. The horizontally opposite hinge points comprise hinge pins 15 extending oppositely outward from hinge blocks 16 and 17. The vertically opposite hinge points comprise hinge pins 18 which extend oppositely outward from lower nut members 19.

The two sets of links 12 are arranged at opposite sides of a vertical tubular shaft 20 which surrounds the operating shaft 14. The horizontally opposite hinge points of each set of four links 12 comprise hinge pins 21 which extend oppositely outward from hinge blocks 22 and 23. The vertically opposite hinge points of the upper links 12 comprise hinge pins 24 which extend oppositely outward from upper nut members 25.

The hinge blocks 16 and 22 are formed on the inside of the front leg portion 10 and the nut blocks 17 and 23 are mounted on a vertical slide bar 26. The rear leg member 11 contains a vertical channel slide 27 which fits over and slidably engages the slide bar 26 to support the rear leg member 11 thereon.

The lower nut members 19 are threaded on right and left hand threads 28, respectively formed on the lower extremity of the operating shaft 14. The upper nut members 25 are similarly threaded on right and left hand threads 29, respectively, formed on the tubular shaft 20.

Thus it can be seen that when the operating shaft 14 is rotated in one direction the nut members 19 will spread so as to separate the lower portions of the leg members 10 and 11 and when rotated in the other direction they will draw the lower portions thereof together. It can also be seen that when the tubular shaft 20 is rotated in one direction it will act to spread the nut members 25 so as to separate the upper portions of the leg members 10 and 11 and when rotated in the other direction it will act to draw the upper portions together.

The selective rotation of the shafts 14 and 20 is accomplished by means of a key sleeve 30 which is slidably mounted upon the upper extremity of the operating shaft 14 above the tubular shaft 20. Two clutch dogs 31 project downward from the sleeve 30 which engage in notches 32 in the upper extremity of the tubular shaft 20 and two notches 33 which can be brought into engagement with a cross-key 34. The sleeve is rotated by means of a handle member 35.

Should it be desired to expand the upper part of the leg portion, the sleeve 30 is forced downwardly until the dogs 31 engage the notches 32. Rotation of the sleeve will now rotate the tubular

shaft 20, causing the nut members 25 to either approach or recede from each other, which action is transmitted through the links 12 to expand or contract the upper part of the leg portions.

Should it be desired to expand the lower part of the leg portions, the sleeve 30 is lifted until the notches 33 engage the key 34. Rotation of the sleeve will now be transmitted to the operating shaft 28, causing the nut members 19 to approach or depart from each other so as to expand and contract the lower part of the leg portions.

A foot member 36, conforming in general to the shape of the forward portion of a shoe last, is hinged upon hinge bolts 37 extending through downwardly-depending ears 38 formed on the front leg portion 10. The foot member 36 is hollow and opens to the bottom, forming a mechanism cavity 39. The bottom of the cavity 39 is closed by means of a bottom plate 40 detachably secured by means of suitable screws 41.

An inclined shaft 42 extends through the cavity 39 and is rotatably mounted therein. The shaft 42 carries two adjacent sets of right and left-hand threads 43. A nut 44 is mounted on each set of threads 43. Two oppositely extending expansion links 45 extend from each nut 44.

A foot stretching member 46 is mounted in each side of the foot member 36, supported by the bottom plate 40. Each of the stretching members 46 carries two hinge pins 47 to pivotal connections on the nuts 44 so that each of the stretching members 46 will be connected with both of the nuts 44. The shaft 42 is rotated through the medium of universal joints 48 from a vertical shaft 49. The upper extremity of the shaft 49 is formed with a key slot 50 to receive the extremity of a T-shaped actuating key 51.

It can be readily seen by anyone with average intelligence that if the key 51 be rotated back and forth, it will oscillate the shaft 42, causing the nuts 44 to move oppositely therealong to expand and retract the stretching blocks 46. It will be noted that the foot portion 36 is free to swing at any desired angle to the axis of the leg portion.

In use, all of the elements of the device are contracted to their smallest positions. The rear leg portion 11 is removed from the bar 26. The foot portion 36 is turned downwardly into partial alignment with the front leg portion 10. The entire device is then lowered into the boot, the forward portion turning automatically into the toe portion of the boot.

The rear leg portion 11 is now inserted into the leg of the boot, with the channel slide 27 engaging the slide bar 26, and is forced downwardly until the lower extremity of the rear leg portion rests in the heel of the boot. The shafts 14, 20, and 49 are now manipulated as desired to stretch the boot at any desired point.

For lengthwise stretching, the shaft 14 is employed, which pushes the lower heel extremity of the portion 11 against the heel counter of the boot so as to urge the foot portion forwardly into the toe thereof. After the stretching has been completed, the entire device is contracted to its smallest dimension and the rear leg portion 11 is withdrawn from the boot to allow the remainder to be easily displaced therefrom.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A boot stretcher comprising: a front leg portion; a back leg portion, said two leg portions cooperating to form a complete structure for insertion in the leg of a boot; a foot portion hingedly mounted on the lower extremity of said front leg portion so as to swing in a vertical plane; foot-stretching blocks mounted in the sides of said foot portion; a tubular shaft extending between said leg portions; oppositely acting nut members threaded on said tubular shaft; toggle links extending from said nut members to the upper extremities of said leg portions so that when said shaft is rotated, said portions will be moved away from each other; an operating shaft extending through said tubular shaft; means on said operating shaft for expanding the lower extremities of said leg portions; and independent means for causing said stretching blocks to approach and recede from each other.

2. A boot stretcher comprising: a front leg portion; a back leg portion, said two leg portions cooperating to form a complete structure for insertion in the leg of a boot; a foot portion hingedly mounted on the lower extremity of said front leg portion so as to swing in a vertical plane; foot-stretching blocks mounted in the sides of said foot portion; a tubular shaft extending between said leg portions; oppositely acting nut members threaded on said tubular shaft; toggle links extending from said nut members to the upper extremities of said leg portions so that when said shaft is rotated, said portions will be moved away from each other; an operating shaft extending through said tubular shaft; oppositely acting threads on said operating shaft; nut members mounted on said threads; links connecting said nut members with the lower parts of said leg portions; means for independently rotating said tubular and said operating shafts; and independent actuating means for causing said foot-stretching members to approach and recede from each other, said shafts and said actuating means being operable from the upper extremities of said leg portions.

3. A boot stretcher comprising: a vertical actuating shaft; a tubular shaft surrounding said actuating shaft; means for rotating either shaft independently; oppositely acting nut members threaded on each of said shafts; an upper set of toggle links extending from the nut members on the tubular shaft; a lower set of toggle links extending from the nut members on the actuating shaft; a front leg portion connected to both sets of toggle links; a vertical slide bar connected to both sets of toggle links; a back leg portion slidably mounted on said slide bar so as to be vertically withdrawable therefrom; and a foot portion mounted on the lower extremity of said front leg portion.

4. A boot stretcher comprising: a vertical actuating shaft; a tubular shaft surrounding said actuating shaft; means for rotating either shaft independently; oppositely acting nut members threaded on each of said shafts; an upper set of toggle links extending from the nut members on the tubular shaft; a lower set of toggle links extending from the nut members on the actuating shaft; a front leg portion connected to both sets of toggle links; a vertical slide bar connected to both sets of toggle links; a back leg portion slidably mounted on said slide bar so as to be vertically withdrawable therefrom; a foot portion hinged to the lower extremity of said front leg

portion so as to swing forwardly therefrom; side-
wardly expanding means incorporated in said
foot portion; and actuating means extending
vertically between said leg portions and being
operatively connected to said expanding means
for expanding the latter.
